METAL AWNING FOR A CASEMENT WINDOW

Robert A. Childers, Claud C. Miller, and Charles Smith, Houston, Tex., assignors to Childers Manufacturing Co., Houston, Tex., a corporation of Texas

Application June 19, 1952, Serial No. 20,277

Term of patent 14 years

(Cl. D21—6)

To all whom it may concern:

Be it known that we, Robert A. Childers, Claud C. Miller and Charles Smith, citizens of the United States and residing at Houston, Texas, have invented a new, original, and ornamental Design for a Metal Awning for a Casement Window, of which the following is a specification, reference being had to the accompanying drawing forming part thereof.

In the drawing:

Fig. 1 is a front view of a metal awning for a casement window showing our new design;

Fig. 2 is an end view thereof, the end not shown being the same as that illustrated; and

Fig. 3 is an enlarged fragmentary view, partly in section, taken on lines 3—3 of Figs. 1 and 2,

representing the corrugated and crimped formation of the front panel and both side portions of the metal awning shown in said figures.

We claim:

The ornamental design for a metal awning for a casement window, as shown and described.
